UNITED STATES PATENT OFFICE.

CHRISTIAN J. HUG, OF HIGHLAND, ILLINOIS, ASSIGNOR TO THE HUG COMPANY, OF HIGHLAND, ILLINOIS, A CORPORATION OF ILLINOIS.

ROAD-SURFACING MACHINE.

Application filed December 27, 1921. Serial No. 524,876.

To all whom it may concern:

Be it known that I, CHRISTIAN J. HUG, a citizen of the United States, residing at Highland, in the county of Madison and State of Illinois, have invented certain new and useful Improvements in Road-Surfacing Machines, of which the following is a specification, reference being had therein to the accompanying drawing.

10 My invention relates to improvements in road surfacing machines and has for its object to provide a mechanism to work (by tamping) the surface of a concrete pavement, by means of a traveling, vibrating 15 tamping tool.

Drawings.

Fig. 1 is a plan view of a machine embodying my invention, parts being broken away. Fig. 2 is a side elevation of the same, parts being broken away. Fig. 3 is a front elevation of the same, parts being broken away. Fig. 4 is an enlarged detail of the tamping-tool, carrying roller and the chain 25 for vibrating the same.

Description.

The machine of my invention embodies the traveling frame 10 supported by the 30 driving wheels 11-11 and rear wheels 12-12; the wheels traveling upon the side-forms or kerbs 13, between which the composition pavement 14 (of concrete or the like) has been laid, whose upper face is intended to be worked or surfaced; the frame 10 carries the platform 15, upon which the motor 16 is supported. The power of the motor shaft 17 is conveyed to the jack-shaft 18 by means of the reciprocal transmission 35 gear indicated as 19, the connecting shaft 20 and the bevel gears 21-22. Upon the jack-shaft 18 is the sprocket 23 from which the chain 24 drives the sprocket 25, the shaft 26 and worm 27, the worm 27 engaging with the gear 28 on the shaft 29, on which shaft 29 the wheels 11-11 are mounted.

The tamping tool 30 comprises a series of slats 31, grouped in multiples upon a series 50 of faces, said slats 31 being arranged parallel to each other and spaced apart as shown in Fig. 3.

The tool 30 is mounted between chains 32-32 which carry blocks 33 in which the 55 axle 34 is carried, the tool 30 being so mount-

ed that its axis is inclined at an angle to its path of travel.

It is desired to rotate the tool 30 by a series of impulses, so that there shall be a lull while the tool is in the position shown in Fig. 3 with the slats 31 upon the bottom face of the tool 30 in contact with the surface of the pavement 13. This is accomplished by means of the drive illustrated, the chains 32 being mounted on the sprockets 35-35 driven by the gear 36, the gear 36 in turn being driven by the mutilated gear 37 driven by the chain 38 from the sprocket 39 on the jack shaft 18.

The blocks 33 are supported on small 70 wheels 40, said wheels 40 traveling in succession upon the lower track 41 and the upper track 42, which are disposed within the frame 10 as indicated in Figs. 2 and 3. The tracks 41-41 are adjustable vertically by means of the eye-bolts 43 (see Fig. 2), and when elevated, the tracks 41 serve to hold the tool 30 out of contact with the surface of the pavement. This adjustment is made for the purpose of transporting the machine 80 in inoperative condition. It will be understood that any desired number of the tools 30 may be employed in any one machine.

The tool 30 being in the position illustrated in Fig. 3, it is desired to impart vertical 85 vibratory movement thereto. This is accomplished by means of a chain belt 44, each of whose links is of such size as to permit the periphery of the wheel 40 to extend through the link and rest upon the track 41. 90 Thus the passage of the chain 44 imparts a vertical jolt to the tool 30 as the wheel 40 is made to jump out of one link, and into the next link, of the chain-belt 44. The chain-belt 44 is mounted as shown in Figs. 95 2 and 3, its upper half resting and traveling upon the upper face of the track 41, the chain-belt 44 being driven by the sprocket 45 and chain 46 from the sprocket 47 on the jack shaft 18.

Claims:

1. In a road surfacing machine a tamping tool comprising a rotatable base having a series of peripheral plane faces; parallel slats mounted on said faces; and means comprising a mutilated gear for successively contacting and holding said faces upon the surface being worked.

2. In a road surfacing machine a tamping tool comprising a rotatable base having a 110

- series of peripheral plane faces; parallel slats mounted on said faces; and means comprising a mutilated gear for successively contacting and holding said faces upon the 5 surface being worked; in combination with a track carrying said tamping tool and means for elevating said track to hold said tamping tool out of working position.
3. In a surfacing machine, a tamping tool 10 having a plurality of flat faces, and means for rotating said tool to bring said faces successively in contact with the surface to be worked, and means for imparting vertical vibratory movement to said tool.
- 15 4. In a surfacing machine, a traveling frame; an endless chain carried thereby and

mounted transversely of the path of travel of the frame; a rotatable tamping tool carried by said chain; and means for rotating said tool by a series of impulses and for vibrating said tool while its bottom face is in contact with the surface of the pavement.

5. In a road surfacing machine a tamping tool having a series of peripheral plane faces; a series of parallel slats grouped in 25 multiples on each of said faces; and means embodying a mutilated gear for rotating said tool and holding said faces successively in contact with the work.

In testimony whereof I hereunto affix my signature.

CHRISTIAN J. HUG.
